UNITED STATES PATENT OFFICE

132,383

DESIGN FOR A TARGET AIRPLANE OR SIMILAR ARTICLE

Robert E. Reedy, North Hollywood, Calif., as-
signor, by mesne assignments, to Vega Aircraft
Corporation, a corporation of California

Application December 6, 1940, Serial No. 97,127

Term of patent 7 years

To all whom it may concern:

Be it known that I, Robert E. Reedy, a citizen
of the United States, residing at North Holly-
wood, in the county of Los Angeles and State of
California, have invented a new, original, and
ornamental Design for a Target Airplane or
Similar Article, of which the following is a speci-
fication, reference being had to the accompany-
ing drawing, forming a part thereof.

Fig. I is a top perspective view as viewed from
the front portion showing a target airplane em-
bodying my new design; and

Fig. II is also a perspective view as viewed from
the front and one side thereof.

I claim:

The ornamental design for a target airplane
or similar article, substantially as shown.

ROBERT E. REEDY.
